UNITED STATES PATENT OFFICE.

LOUIS W. BERGESCH, OF ST. LOUIS, MISSOURI.

BURIAL-CASKET HANDLE.

1,403,666.

Specification of Letters Patent. Patented Jan. 17, 1922.

Application filed August 29, 1919. Serial No. 320,569.

To all whom it may concern:

Be it known that I, LOUIS W. BERGESCH, a citizen of the United States, residing at the city of St. Louis and State of Missouri, **5** have invented a new and useful Burial-Casket Handle, of which the following is a specification.

This invention relates to burial casket handles.

10 An object of the invention is to provide an improved burial casket handle, embodying a construction by which many of the parts may be stamped out of plate metal or sheet metal and which, when assembled **15** and applied as a finished handle, form a strong and durable construction.

Another object of the invention is to provide a handle for burial caskets in which many of the parts of the handle may be **20** economically stamped out of metal plates or sheet metal, and in which the manually engageable part or handle bar of the handle is connected to and retained in connection with the pivoted members by means of novel **25** and improved construction.

An additional object of the invention is to provide a handle of the character and for the purpose stated, or for other uses, in which the pivoted members of the handle are **30** connected to and made to co-operate with their supports by a novel and improved construction and arrangement.

With the foregoing and other objects in view, I have produced an improved burial **35** casket handle, and have illustrated the same in the accompanying drawings, in which:—

Fig. 1 is an assembled view of one embodiment of the invention.

Fig. 2 is an end elevation of the handle.

40 Fig. 3 is a sectional view on the line 3—3 of Fig. 1.

Fig. 4 is a view partly in section illustrating certain features of the invention.

As illustrated, the supporting members **45** which are secured to the wall of the burial casket are formed of plate metal or sheet metal stamped or pressed to provide an outer wall 1 of the desired size and design, and a flange 2 bordering the wall 1 and arranged **50** so that the edge of said flange bears and fits against the wall of the casket to which the handle is applied. The handle may be secured to the wall by fasteners 3. The wall 1 of each supporting member is **55** cut to form an opening and the material

above and at the sides of the opening is pressed outwardly to form a flange 4, bordering the opening and functioning to co-operate with the pivoted member of the handle as will hereinafter appear. The material at the lower side of the opening so formed is utilized to form an upwardly extending tongue, the extremity of which is curved as shown at 5 in order to extend around the inner side of a pin or small rod **60** 6 by which the pivoted member of the handle is supported.

Each pivoted member of the handle is also composed of plate metal or sheet metal stamped or pressed to form an outer wall **70** 7, side walls 8, a lower end wall 9, and a curved upper wall 10 united to the outer wall by a wall portion 11 formed approximately at right angles to the outer wall 7 and constituting a shoulder to bear against and co-**75** operate with the flange 4 when the casket is being carried or supported by the handles, as will readily be understood by reference to Fig. 3. The upper portion of the members **80** 7 extends into the opening formed in the co-operating supporting member, and the tongue 5 is between the side walls 8. The pin or rod 6 engaged by the tongue 5 as described, extends through the side walls 8 and projects a sufficient distance beyond the **85** side walls 8 to effect proper engagement with the inner surface of the supporting member of the handle. When the handle members are in their idle or dependent positions, the curved walls 10 close the openings in the **90** supporting members and give a finished appearance to the handle. When the casket is supported by the handles, the shoulders **95** 11 contact with the flanges 4 and by co-operation with the pins or rods 6 form a construction by which the casket may be supported and carried.

The manually engageable part or handle bar 12 is connected to the pivoted supporting members by convenient and efficient **100** means. As shown, the side walls 8 of the pivoted members of the handle are cut to form recesses or notches in which the handle bar 12 is seated. The material of the side walls 8, at the sides of the notches, is bent **105** inwardly in the form of tongues 13. Retaining clips 14 pass partly around the handle bar 12 at each pivoted support and extend between the bar and the tongues 13. The ends **110** 15 of said clips are bent against

the tongues 13 as shown, thus, securely holding the handle bar in position.

It will be understood that each handle bar is supported by a pair of devices constructed 5 as described, one of said devices being near the end of the handle bar. The portion of the handle bar which is between the supporting device constitutes the manually engageable portion so that it is necessary to 10 locate the supporting devices apart a sufficient distance for the end to pass conveniently between them.

From the foregoing, it will be understood that I have produced an efficient handle 15 which may be economically constructed, and which efficiently serves its purpose.

I do not limit myself to unessential fea-

tures, but what I claim and desire to secure by Letters Patent is:—

A device of the character described comprising a support; in combination with a handle support supported by said first-named support and composed of sheet metal folded to provide an outer wall, and side walls, said side walls having recesses near 25 their lower end; a handle bar seated in said recesses; flexible projections integral with said side-walls above and below said handle bar and extending inwardly from said side walls; and a clip extending partly around 30 said handle bar and having its ends interlocking with the inner edges of said projections.

LOUIS W. BERGESCH.
